(57) **CLAIM**

The ornamental design for a vehicle fender flare, as shown and described.

DESCRIPTION

FIG. 1 is a perspective view of a vehicle fender flare, for the left side of a vehicle, according to the design of the present invention.

FIG. 2 is a second perspective view, generally from the front, of the vehicle fender flare seen in FIG. 1.

FIG. 3 is a third perspective view, generally from the rear, of the vehicle fender flare seen in FIG. 1.

FIG. 4 is a top view of the vehicle fender flare seen in FIG. 1.

FIG. 5 is left side view of the vehicle fender flare seen in FIG. 1.

FIG. 6 is a bottom side view of the vehicle fender flare seen in FIG. 1; and,

FIG. 7 is a right side view of the vehicle fender flare seen in FIG. 1.

A vehicle fender flare, for the right side of a vehicle, being a mirror image of the vehicle fender flare seen in FIGS. 1-7. In the drawings, the broken lines depict portions of the vehicle fender flare which do not form part of the claimed design. The drawings include a symbolic break. The portion between the break lines forms no part of the claimed design. Shade lines having a combination of long and short lines in the drawings show contour and not surface ornamentation.
